UNITED STATES PATENT OFFICE.

BROR JOHANNES BENGTSSON, OF KALLERED, SWEDEN.

HOLDER FOR CLEANING NEEDLES FOR VAPORIZING BURNERS OR THE LIKE.

Application filed August 21, 1922. Serial No. 583,440.

To all whom it may concern:

Be it known that I, BROR JOHANNES BENGTSSON, a subject of the King of Sweden, residing at Kallered, in the county of Göteborg and Bohus and Kingdom of Sweden, have invented new and useful Improvements in and Relating to Holders for Cleaning Needles for Vaporizing Burners or the like, of which the following is a specification.

- 10 The present invention relates to holders for cleaning needles provided to be used for the cleaning of the orifice of vaporizing burners and similar appliances and especially to such a holder which comprises a resilient double-shanked pincer like handle, one shank of said handle carrying the needle proper and the other shank serving as a guide for said needle when said shanks are mutually moved.
- 15 20 This invention has for its principal object to provide a holder of the type specified, which will be extraordinary effective to save the needle from lateral strains when in the operation for cleaning the burner or the like.

Another object of the invention is to provide means, which will enable the implement to be easily applied upon the orifice of the burner in exact position for the cleaning purposes even in darkness and if the burner should be entirely clogged up by deposits or impurities.

Another object of the invention is to provide means for the easy and safe application and removing of the needle on the holder.

Another object of the invention is to provide a needling device by which the operator's hand will be safe-guarded from damages by the heat of the flame from the burner during the cleaning operation.

Still another object of the invention is to provide a needling device which is handy in operation and which will be easily and cheaply manufactured and conveniently portable.

Other objects of the invention will be evident from the following description with reference to the accompanying drawing illustrating two embodiments of the same invention. In said drawing Fig. 1 shows in side elevation the one embodiment of my improved holder in nonoperative position; Fig. 2 shows a similar view of the same holder in enlarged scale in operation and partially in section; Fig. 3 shows on the same scale a section of the holder on the

line A—A in Fig. 1; Fig. 4 is a view of a detail on the same scale as in Figures 2 and 3; Fig. 5 shows a portion of the holder in side elevation; Fig. 6 shows a portion of the holder from the underside; Fig. 7 is a plan view of a device for keeping spare needles in store; Figures 8 and 9 is a section and an end elevation respectively of said storing device; Fig. 10 shows in a side elevation a holder according to the other somewhat modified embodiment nonoperative and Fig. 11 shows a portion of the last mentioned holder when in use and partially in section.

According to the embodiments shown the holder comprises a resilient metal ribbon, which is bent in the form of a U with the curved junction portion 1 of the U widened annularly and serving as a handle for the operator. From this curved portion the substantially straight shanks 2 and 3 extend substantially parallel when nonoperative and normally kept apart from each other by means of the resilient action of the annular portion 1 as shown in Fig. 1. The free end portion 4 of the shank 2 is twisted in about a quarter of a turn such, that its flat side is substantially perpendicular to the flat side of the shank 3. The edge 5 of the shank 2 opposite to the shank 3 adjacent to the outer end is flanged down as shown in the drawing. Adjacent to this edge there is fastened a plate-strip or tongue 6, which narrowly passes through a corresponding slot 7 in the shank 3, so that when moving the shanks mutually they are strictly guided in the moving plane by the cooperation of the tongue 6 and the slot 7. The bottom edge 8 of the tongue 6 positioned below the shank 3 is somewhat enlarged in width so as to prevent its passing through the slot 7 in order to avoid the shanks 2, 3 from being spaced apart from one another by the resilient action of the annular portion 1 above a certain degree as shown in Fig. 1, in which the widened edge 8 of the member 6 bears against the shank 3 all round the hole 7. Of course the same effect can be obtained by any other provisions as for instance a stop pin passed laterally through the tongue 6 below the shank 3.

Adjacent to the edge 5 at the free end 24 of the shank 2 a rectangular plate 9 is detachably applied by means of a screw 10 with a rifled head. As clearly shown by Fig. 4 the plate 9 is provided with a rather narrow groove 11, which forms the seat for

the cleaning needle 12 proper of the ordinary kind. By means of the screw 10 said needle is clamped in the groove 11 between the member 9 and the shank 2. The nonoperative upper end of the needle 12 in this position bears against the flanged edge 5 and by this means the displacement of the needle rearwards when forced through the clogged orifice 17 of the burner-nozzle 18 is prevented. The groove 11 naturally also may be formed in the shank 2 instead of the member 9 or both in the shank 2 and in the member 9. In any case however, the total width of the groove must be narrower than the thickness of the needle, so that the latter, when tightening the screw 10, will be firmly clamped on to the shank 2 and thus secured in place.

The operative end of the needle 12 projects into a narrow hole 13 in the shank 3, the said hole having practically the same width as the diameter of the needle.

On the underside of the shank 3 there is formed an annular cavity 20 disposed coaxially to the hole 13 and with substantially the same width as the outer diameter of the burner-nozzle to be cleaned, which nozzle is diagrammatically shown in the drawing and marked with the reference 30 Figure 18.

On the rear side of said cavity there is a fork-shaped projection 22, the bottom of which is substantially semi-circular in shape and disposed in alignment with the annular 35 wall of the cavity 20.

As shown by Figures 1 and 2 the outer ends 24 and 25 of the shanks 2 and 3 respectively are bent such that when the implement is kept in the position illustrated by 40 Fig. 1 with the operative end of the needle 12 turned downwardly, the said ends are positioned on a higher plane than the outer portions of the respective shanks for the purpose explained below.

To the shank 2 of the holder there is 45 removably attached a casing 16 for spare needles. This casing 16 according to the Figures 1, 5, 6, 7, 8 and 9 comprises a gutter-shaped member, the longitudinal 50 edges 26 of which are bent down so as to form folds adapted to embrace the shank 2 as shown in Fig. 1. The bottom of said gutter is provided with a lower portion 27, which in both ends is finished by inclined planes 28, 29 with a suitable inclination, say some 45 degrees. The bottom portion 27 is crossed by a transverse beam 30 which is positioned as high above the bottom portion 27, that spare needles 12¹ may be positioned 60 below the beam 30 with their ends resting on the inclined surfaces 28, 29 respectively. These spare needles can be removed off from the casing by being pushed against either of the inclined surfaces 28, 29, whereby the 65 needles influenced by their resilient ability

are brought to the position assumed by the needle 12^a in Fig. 8, from which position the needle can be fully removed without further trouble.

The casing 16 is applied upon the shank 70 2 by pushing it in from the down flanged narrower portion 5 of the shank 2 (see Fig. 5) to the not flanged wider portion of the same shank, in which last mentioned portion the bent edges 26 partially embrace 75 the shank 2 (see Figures 1 and 6). When a spare needle is to be taken out off from the casing 16, the latter is removed from the shank 2 in the opposite way.

The casing 16 may also be applied to the 80 holder in any other convenient way for instance by means of a pin, which permits the rotation of the casing 16 from the position shown in Fig. 1 to a position, from which the needles may be freely removed. Such as embodiment, however, is not shown in the drawings, as it is mentioned only to show that I do not want to limit myself 85 to any special device for the spare needle casing.

The operation of the device will now be explained.

When cleaning the orifice 17 of the burner nozzle 18 the implement with the shanks 2, 3 spaced apart from each other, so far as the stopping device 8 allows is placed with the outer end of the shank 3 against the upper end of said nozzle. When pushing the implement horizontally as indicated by the arrow in Fig. 2 the fork-shaped portion 22 guides the implement such, that the cavity 20 is brought straight above the nozzle 18, which thereby enters the cavity 20. The hole 13 thus is easily placed centrally to the orifice 17 even if the latter should be clogged by impurities or deposits or if the cleaning operation is performed in darkness. The needle 12 is now forced down into the orifice 17 by pressing the shank 2 downward against the shank 3 100 as shown in Fig. 2. During this operation the needle 12 is guided by the hole 13 and obtains thereby the required lateral support. The shank 2 during the same movement is guided by the tongue 6 and the slot 7 which 110 take up any lateral strains upon the shanks, and consequently the very thin and rather soft needle 12 will always maintain its linear and central position in relation to the orifice 17 and not be bent or clogged against the 120 wall of the hole 13.

If the burner is lighted during the cleaning operation the bent up outer end 25 of the shank 3 prevents the flame from being spread out backwardly and consequently 125 serves as a heat protecting screen for the operator's hand.

By means of the bent up shape of the outer ends 24, 25 of the shanks also the advantage is attained, that the needle 12 130

can be given the requisite length also in such cases, in which the burner as usually known is surrounded by a ring for the cooking utensil, which ring would prevent the insertion above the burner nozzle of a holder of such a straight lined form as shown in Figures 10 and 11.

I do not want to limit myself to the embodiment above described and shown in the Figures 1-6. For instance my invention also includes a holder with substantially straight lined shanks as shown in Figures 10 and 11, as also according to these figures the cavity 20 in the shank 3 in the embodiment described may be substituted by a plate 19 fastened to the lower side of said shank and provided with a hole 20¹ of the same width as the substituted cavity 20, and the forked-shaped projection 22 may be substituted by a correspondingly shaped plate-strip 21 having an extension 23 angle bent to the forked-shaped portion 22, so as to form a heat protecting screen.

In the figures last referred to the casing 16 for spare needles has been given the shape of a socket closed in the one end and open in the other end and by this end fastened in a corresponding hole in the annular portion 1 of the holder by means of a nut 15, which simultaneously forms the cover for the casing.

Of course the modifications of the catching device 20 the screen 23 and the casing 16 can be applied in various combinations to each other.

What I claim is:

1. In holders for cleaning needles for vaporizing burners, a resilient double-shanked pincer like handle, means on one shank of the handle for securing a cleaning needle, means on the other shank of the handle for guiding the needle through the orifice of a burner nozzle to be cleaned, and independent guiding means provided near the free ends of the shanks for positively preventing lateral strains on said needle.
2. In holders for cleaning needles for vaporizing burners, a resilient double-shanked pincer like handle, means on one shank of the handle for securing a cleaning needle

thereto, guiding means for said needle on the other shank of said handle, one of the shanks being also provided with a slot, and a projection extending from the opposite shank of the handle for cooperating with the slot so as to guide said shanks laterally in relation to each other independently of said needle.

3. In holders for cleaning needles for vaporizing burners, a resilient double-shanked pincer like handle formed from a single piece of metal, means on one shank of said handle for detachably clamping a needle, said means including a clamping member on one side of the shank of the handle, a set screw for forcing said clamping member against the side of said shank, the clamping surfaces of the member and the shank being provided with a groove having a depth less than the thickness of the needle so as to ensure of the firm fixing of the needle between the clamping surfaces upon the tightening of said screw and a needle guide formed on the other shank of the handle for guiding the needle in its axial movement when the shanks of the handle are moved relative to each other.

4. In holders for cleaning needles for vaporizing burners, a resilient double-shanked pincer like handle formed of a single piece of metal, means for detachably securing a needle on the end of one of the shanks of said handle, means on the other shank of said handle for guiding the needle in its axial movement, the last mentioned shank being also provided with an annular flange disposed coaxially with said needle and shaped to fit the upper end of the burner nozzle to be cleaned and a fork-shaped member adjacent to said annular flange and adapted to guide the holder when moved longitudinally to the burner nozzle so that the flange may be brought to engage said burner nozzle.

In testimony whereof I have affixed my signature.

BROR JOHANNES BENGTSSON.
